UNITED STATES PATENT OFFICE.

JOHN H. MAGEE, OF CARTHAGE, MISSOURI.

WALL CONSTRUCTION OR WALL.

1,399,222.

Specification of Letters Patent.

Patented Dec. 6, 1921.

Application filed June 11, 1919. Serial No. 303,344.

To all whom it may concern:

Be it known that I, JOHN H. MAGEE, a citizen of the United States, residing at Carthage, in the county of Jasper and State 5 of Missouri, have invented certain new and useful Improvements in Wall Constructions or Walls, of which the following is a specification.

My invention relates to a wall construction or wall, containing relatively large mineral aggregates, coated with a binder of cement, in the central or body portion thereof.

In the construction of the ordinary concrete walls, for buildings and the like, it is customary to employ heavy or strong molds, which are ordinarily formed of boards, iron or the like. The concrete is ordinarily in a more or less plastic or semi-liquid state and 20 is poured into the spaces of the mold. It is obvious that such mold must be sufficiently strong in order to hold the plastic or semi-liquid concrete before the same sets.

In accordance with my process, I am able 25 to dispense with the use of the heavy or strong molds, made of wood or iron, and employ in their place relatively thin or narrow laths, attached to uprights or studs, which may be of the ordinary dimensions 30 or consisting of two transversely spaced upright face pieces bonded together at intervals by narrow laths, and which become a permanent part of the wall and function to reinforce the same. I take irregular aggre-

35 gates, such as stone, brick, slag or the like, which has been broken into relatively large portions and screened clean of all finer particles and foreign matter, and completely coat the same with a plastic or semi-liquid 40 cement or other binder by suitable mixing. After being thoroughly coated on all sides, the aggregates are introduced into the inner space between the laths and allowed to remain undisturbed a sufficient length of time 45 for the cement to set and form the body portion of the wall. The coarse mineral aggregates, after setting, are bonded merely at their meeting edges, and a substantially porous body portion, which will always re- 50 main dry, is obtained. Heretofore, it has been believed that a solid wall is necessary to obtain the necessary strength in building operations, but I have found that the strength of a wall built in the above men- 55 tioned manner is a great deal in excess of actual requirements and the wall has the

advantage of being substantially porous and will thus remain dry at all times. It has been found that the outer portions of the mass of coarse aggregates will tend to project to some extent outwardly through the spaces between the laths and the entire mass is more or less porous or containing voids. By reason of this construction, the outer coating of the wall, which may be 60 formed of plaster or other suitable cementitious material, may be readily forced into the spaces between the laths and into the adjacent cavities or voids of the body portion of the wall, thereby insuring a secure 65 anchoring of the outer coating or plaster to the body portion of the wall.

In the accompanying drawings forming a part of this specification and in which like numerals are employed to designate like 70 parts throughout the same:

Figure 1 is a side elevation of a wall embodying my invention, parts being broken away for the purpose of illustration;

Fig. 2 is a vertical transverse section, 80 taken on line 2—2 of Fig. 1;

Fig. 3 is a fragmentary detail section through the wall, showing the manner of anchoring the parts together;

Fig. 4 is a perspective view of one of the 85 vertical uprights;

Fig. 5 is a plan view of a slightly different form of wall; and

Fig. 6 is a transverse sectional view, taken 90 on line 6—6 of Fig. 5.

In the drawings, wherein for the purpose of illustration is shown a preferred embodiment of my invention, attention being called first to Figs. 1 and 2, the numeral 5 designates vertical uprights as a whole. 95 Each upright is preferably constructed of a pair of vertical pieces or beams 6, spaced as shown, and connected by laths 7, arranged upon the opposite sides thereof. These laths are preferably spaced for a substantial distance, such as for one foot while this distance may be suitably varied as may be found advantageous. The uprights 5 are arranged in transverse pairs and may be held in the vertical position by any suitable 100 means. Transverse spacing members 8 are arranged between the uprights and may be attached thereto by nails 9 or the like. These spacing members 8 are preferably angularly or diamond-shaped in cross section, as 110 shown.

Attached to the outer surfaces of the up-

rights 5 are preferably horizontal outer laths 10, which are preferably formed by sawing the ordinary commercial lath longitudinally into two portions providing laths 5 which are about $\frac{1}{16}$ of an inch thick and $\frac{1}{8}$ of an inch in width, while the invention is of course in no sense restricted to these precise proportions.

The commercial lath may be cut diagonally, providing inclined faces 11, as shown. The laths 10 are preferably arranged about one-inch apart, but this distance may be varied as found advantageous.

As more clearly shown in Figs. 2 and 3, the space between the uprights 5 and the laths 10 is filled with relatively large mineral aggregates 12, and I prefer that these mineral aggregates be of a size that will pass through a screen of one-inch mesh, and be retained on a screen of one-half inch mesh, while this precise size may be varied. The mineral aggregates may be broken stone, bricks or the like, and it is to be distinctly understood that these mineral aggregates are not finely divided, such as pulverized or crushed, but are relatively large irregular pieces, screened clean of dust and fine particles. Prior to being introduced into the space between the uprights and laths these relatively large mineral aggregates have all sides thereof thoroughly coated with a semi-liquid or plastic cement, or other cementitious material or binder, by suitable mixing. After the relatively large mineral aggregates are thus coated, they are introduced into the space between the uprights and laths and are allowed to set and harden. These mineral aggregates become the main body of the wall which is continuous by incorporating the hollow open work uprights 5 as a part thereof, particular attention being called to the fact that these mineral aggregates pass into the hollow uprights filling the spaces therein. These hollow open work uprights do not interrupt the integrity of the wall. The mineral aggregates produce a wall, which is provided with relatively large voids throughout its cross sectional area, it being distinctly understood that the cementitious material is simply applied to the surface of the mineral aggregates in a proper amount to coat such surfaces, but is not present in a sufficient amount to fill the voids between the mineral aggregates. As more clearly shown in Fig. 3, the outer portions of the mineral aggregates pass or project more or less into the spaces between the laths 10, interlocking therewith and forming a highly irregular surface. This is an important feature.

The aggregates forming the main body of the wall are thus arranged to produce a substantially porous structure and, at the same time, are secured to each other at

their meeting edges by the cementitious coating. The wall formed has sufficient strength to withstand the stress to which it is subjected in practical use.

The numeral 13 designates a coating or facing, which is applied to the exterior surface of the wall embodying the mineral aggregates, and which coating or facing may be formed of ordinary plaster, mortar or other cementitious material. Portions of the coating 13 extend between the laths 10 and become anchored to the projecting portions of the mineral aggregates between the laths, thereby penetrating the voids in the outer portion of the wall for a substantial distance, whereby such coating is securely anchored to the body portion of the wall.

Particular attention is called to the fact that the vertical members and laths become permanently embedded or inclosed within the material of the wall, and they function as reinforcing means for the same while being protected and surrounded by the material of the wall from the action of the air or weather, thereby prolonging their life.

In Figs. 5 and 6, I have shown a hollow wall construction, embodying wall sections 14. Each of these wall sections are similar to the wall shown in Figs. 1 and 2 and comprises hollow open work uprights 15 similar to the uprights 5 but having a slightly different shape. Laths 16 are secured to the opposite sides of the uprights 15 in spaced relation, as shown. Transverse laths 17 are secured to certain of the uprights 15, and project between the laths 15 which are continuous and provide a transverse form, serving to connect the wall sections. The space within the wall sections 14 is filled by the relatively large mineral aggregate 18 coated with the cementitious material which passes into the hollow open work uprights 15; and the space between the transverse laths 17 is also filled with the relatively large mineral aggregates to produce a transverse column 19. A coat 20 is applied to the outer surface of the wall sections 14.

It is to be understood that the forms of my invention herewith shown and described are to be taken as preferred examples of the same, and that various changes may be resorted to without departing from the spirit of the invention or the scope of the subjoined claims.

Having thus described my invention, I claim:

1. In a wall construction, a skeleton frame formed of two sets of laths, a filler of relatively large mineral aggregates arranged within the space between the two sets of laths, said aggregates having their surfaces coated with a cementitious material, the filler being of such size as to produce voids throughout the wall but being bonded at the meeting edges of the aggregates, and

an outer coating of cementitious material secured to the exposed surface of the laths, and engaging the surface of the filler.

2. In a wall construction, a skeleton frame formed of vertical uprights arranged in two sets to form the front and back of the wall, and spaced laths secured to the outer sides of the uprights, a filler of relatively large mineral aggregates arranged within the space between the laths, said aggregates having their surfaces coated with a cementitious material, the filler being of

such size as to produce voids throughout the wall but being bonded at the meeting edges of the aggregates, and an outer coating of 15 cementitious material secured to the exposed surface of the laths, and engaging the surface of the filler.

In testimony whereof I affix my signature in the presence of two witnesses.

JOHN H. MAGEE.
